Atlys.

Patented May 28, 1929.

UNITED STATES PATENT OFFICE

CHARLES A. SCOTCHER, OF BROOKLINE, MASSACHUSETTS, ASSIGNOR TO S. C. S. BOX COMPANY, OF PALMER, MASSACHUSETTS, A CORPORATION OF MASSACHUSETTS.

RECEPΤΑCLE OR CARTON AND LOCKING MEANS THEREFOR.

Application filed August 18, 1927. Serial No. 213,804.

My present invention relates to receptacles or containers such as cartons, boxes or the like, and more particularly aims to provide in connection therewith improved means for securing the cover or closure in closed position. This application, as to all common subject matter, is a continuation of my co-pending application Serial No. 164,462, filed January 29, 1927.

10 In the accompanying drawings illustrating by way of example one embodiment of my invention;

Fig. 1 is a perspective view of a box or carton in accordance with one form of the present invention, the cover being partially open;

15 Fig. 2 is a vertical cross-section upon a larger scale centrally through the carton of Fig. 1 with the cover closed and locked by the securing means;

20 Fig. 3 is a front elevation of that portion of the carton at which the securing means is provided, the same being locked as in Fig. 2;

Fig. 4 is a detail view in cross section illustrating a manner of locking the securing

25 means;

Fig. 5 is a horizontal section on the line 5, 5 of Fig. 2 taken through one securing or locking unit in the locking position thereof; and

30 Fig. 6 is a perspective of the upper portion of a different type of receptacle also embodying one form of my invention.

Closure retaining means embodying my invention may be variously employed and in connection with receptacles of different types, forms and materials, but, as in my copending application above mentioned, is particularly useful in cartons or boxes of card board or like flexible but desirably self-supporting material, including, for example, egg cartons, pastry and doughnut boxes, candy boxes, etc.

35 The receptacle with which I have chosen to show my invention is the same as that of my co-pending application, being a collapsible 40 carton of the so-called "Victor" type, similar to that of my U. S. Letters Patent No. 1,374,473, dated April 12, 1921.

45 Referring more particularly to the drawings and first to Fig. 1, the receptacle or carton there shown comprises a body 5 including a bottom, opposite side and end walls, and a closure member, top, or cover 6 provided with a flange or tuck 7. While, as illustrated, said cover comprises a single piece having the 50 width of the carton it may be otherwise

formed if desired. In the carton bottom and end walls is a median line of weakness or score 8 and also in the carton bottom are inclined lines of weakness or scores 9, 9 etc. extending preferably from the corners and 60 forming triangular portions 10, 10.

By reason of said lines of weakness or scores the carton may be collapsed, as in my said patent, bringing the front and rear walls together flatwise, the bottom and end walls 65 being infolded along said median lines of weakness. As represented, the end walls are provided with flanges or flaps 11, 11 which, in the closed position of the carton, are adapted to serve as stops or supports for the 70 cover and afford additional protection for the contents adjacent the carton ends. The median score 8 is also extended through said flanges 11, 11 when present.

Assuming that the carton is in collapsed 75 condition, it may readily be set up by pressure directed downwardly against the score line 8 at any point along the base or where said line extends along the carton end walls. The carton may then be filled and the end 80 flanges and the cover 6 closed down, bringing the flange or tuck 7 flatwise against the upper portion of the front side wall either outside or inside it, preferably inside.

The cover securing means of my present 85 invention is particularly useful in connection with a cover having a flange or tuck such as said member 7 for positioning inside the adjacent carton wall. Referring to the drawings said means as illustrated comprises a 90 tongue 18 cut out from the tuck 7 and supported along one edge, herein its upper edge 19, substantially in the line of fold of the tuck. Said tongue may be of any desired shape, 95 preferably of somewhat decreasing width downwardly, and terminates in a lower portion or lug 20 of roughly rectangular shape and having oppositely laterally extending ears 21, 21.

The tongue 18 is cut free from the cover and flange or tuck along its entire periphery with the exception of its line of hinged support 19 so that when the tuck is folded along its hinge line, said tongue is sprung slightly outwardly, substantially as illustrated in Fig. 1. On closing the cover and as the tuck is inserted within the adjacent wall of the carton, herein the front wall, the tongue remains at the outside of said wall.

Upon said front wall of the carton, and at 110

- a position opposite the lower portion or lug 20 of the tongue 18, is a formation whereby said lug may be forced inwardly, through and across the plane of the carton front wall substantially as shown in Figs. 2, 3 and 4. Said formation may be variously provided but preferably includes an upwardly extending tab 22 supported along one side only, herein its bottom side, as at 23, and adapted 10 to be bent inwardly leaving an opening in the carton wall.
- One method of fastening or locking the carton securing means or lock is illustrated in Fig. 4. The lug 20 of the tongue 18 having 15 been brought opposite and outside the tab 22 upon the carton front wall, and the tuck 7 having been inserted within said wall, said lug and tab may be simultaneously thrust inwardly, as by means of a finger tip, a pencil 20 or any suitable instrument, the point of which is preferably swung somewhat upwardly when within the carton. The lug 20 is thus forced upwardly sufficiently to retain it in the manner of a hook within the carton. In 25 the construction illustrated the lug is caught and held locked by the upper edge of the in-turned tab 22, as shown in cross section in Fig. 2. The width of the lug 20, including the ears 21, 21 if provided, may be varied, so 30 long as the lug can readily be thrust through the opening provided in the carton wall. Preferably the lug width is slightly in excess of that of the tab 22 and opening formed by it, in which case the lug 20 is retained and 35 the cover locked additionally by reason of the sides of the lug and herein the ears 21, 21 springing out to either side of the opening made by the lug 22; see Fig. 3.
- It will be noted that in operating the closure locking means the slight pressure necessary to thrust in the lug 20 is exerted against and received by the carton front wall, by reason of the tongue 18 being outside that wall and does not come against the carton 40 contents. The tongue 18 is pushed downwardly and inwardly and its lower end or lug 20 thrust through the adjacent carton wall and through the opening left by the tongue in the flange or tuck 7. Said tongue 18 thus not 45 only draws that wall and the entire tuck firmly together, closing the usual gap between them, but also acts to brace the entire carton circumferentially and in all directions transversely making an extremely firm 50 package, substantially as if all its walls and cover were continuous and integral, or as if a band or cord were fastened tightly about it.
- The carton locking means described, if desired, may be employed in connection with 55 securing means such as disclosed in my co-pending application above mentioned, including a lug 12 hinged at 13 and a cooperating lug 14 oppositely hinged as at 15, one set of such lugs at opposite sides of the lock already described being shown in Fig. 1. One
- unit or set of said securing elements, locks or tabs 12, 14 is also seen in Fig. 2 and upon a larger scale in Fig. 5. As best seen in Fig. 5, it will be noted that the lug 12 on the outer carton portion is readily movable through or across the inner carton portion through the opening formed by the cooperating lug 14 and thereby serves to prevent relative movement of said portions in an opening direction, that is, in a direction substantially 75 in or parallel with the planes of said portions. The relative proportions and arrangement of said lugs may be varied as described in specific instances. It will also be understood that any desired number of units or sets of said devices may be employed depending mainly on the dimensions of the receptacle, and that they may be used alone or in conjunction with the tongue device of Figs. 1 to 4. In some instances one set or unit may 80 be sufficient, these devices being intended for disposal at any point upon the receptacle where it is desired to lock two or more adjacent portions having a relative movement from closed position in approximately the 85 plane of one of said portions or substantially parallel thereto.
- In Fig. 6, I have illustrated locking means embodying one form of my invention in connection with a receptacle or box of the usual 90 removable, flanged-cover type, such as a clothing or candy box. The set or sets of cooperating lugs 12 on the body 16 of the receptacle, and 14 on the closure element 17, may be provided in any one, or more, or all 95 of the receptacle side walls, and may be constructed and proportioned in a manner similar to that described in connection with Figs. 1 to 5.
- My invention is not limited to the specific 100 embodiment thereof herein shown and described, its scope being set forth in the following claims.
- I claim—
1. In a receptacle of flexible material including a body and a closure having a flange adapted for insertion within and flatwise against an adjacent wall of the body, a tongue cut out from said flange and hingedly connected to the closure substantially in the line 110 of the upper edge of the flange, said tongue adapted to be positioned outside said body wall and having a lower portion adapted to be bent inwardly, and a cooperating formation on the body wall opposite said lower 115 tongue portion comprising a lug cut out from said body wall and hinged thereto along its lower edge, said lower tongue portion and said lug being adapted to be thrust inwardly together, broadside and at substantially right 120 angles to the plane of the wall, said lug engaging said lower tongue portion to retain it in said inward or cover-locking position.
  2. In a carton having a bottom and side walls, a cover having a tuck for insertion 125

within and flatwise against one side wall, a downwardly extending tongue cut out from said tuck, terminating short of the lower edge thereof and hinged to the cover in a manner 5 permitting it to extend down along the outer face of the carton wall inside which the tuck is inserted; an inwardly bendable lug at the lower end of said tongue, and a cooperating cut-out formation on said carton wall to allow 10 said lug to be thrust broadside inwardly through said wall and through the opening in the tuck left by the cutting out of said tongue and lug, whereby the cover tuck and the adjacent carton wall are drawn together substantially 15 to close any gap between them and the carton is braced transversely thereof, the cover being at the same time locked in closed position, said lug having lateral portions of a total width exceeding that of said cut-out 20 formation on said carton wall, said lateral portions adapted to yield to permit said in-thrusting of the lug and then to re-open to prevent withdrawal of said lug.

3. In combination with a plurality of carton portions juxtaposed in approximately parallel planes, means to secure said portions against relative movement substantially in or parallel to said planes, said means comprising a plurality of opposed and oppositely hinged lugs, respectively cut out from different ones of said portions, and arranged to be simultaneously thrust inwardly by a force applied at substantially right angles to said 25 carton portions.

4. A receptacle comprising a body and a closure, the latter having a flange or the like at an angle to its main portion adapted to be positioned flatwise adjacent a portion of the carton body in the covering position of said closure, a hinged lug on said flange, a similar 40 lug on said adjacent portion of the carton body having its hinge line substantially diametrically opposite to that of said first lug, said lugs coming opposite each other in the covering position of the closure and adapted 45 to be thrust inwardly together to retain the latter in said covering position.

5. In a carton having a cover including a body and a depending strip at one edge thereof, and having a wall adjacent which said strip is positioned flatwise in the closed position of the cover, a lug on the cover hingedly supported along one of its edges and free along the remainder of its periphery, and a similar lug on the carton wall, opposite said 50 cover-carried lug but hinged along a diametrically opposite edge, said lugs adapted to be thrust inwardly together across the planes of said wall and strip, moving respectively about their opposed hinged edges, into a position wherein they resist relative movement of said cover strip and wall away from each other in their respective planes and wherein one lug locks the other in said restraining 55 position.

In testimony whereof, I have signed my name to this specification.

CHARLES A. SCOTCHER.
